(57) **CLAIM**

The ornamental design for an electrosurgical generator display screen with transitional graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the electrosurgical generator display screen with transitional graphical user interface showing a first image;

FIG. 2 is a front view of the electrosurgical generator display screen with transitional graphical user interface showing a second image; and,

FIG. 3 is a front view of the electrosurgical generator display screen with transitional graphical user interface showing a third image.

The appearance of the transitional image sequentially transitions between the images shown in FIGS. 1-3. The process or period that one image transitions to another image; forms no part of the claimed design.

In FIGS. 1-3, the dot-dash broken lines represent unclaimed boundary lines and form no part of the claimed design. The dash-dash broken lines are for the purpose of illustrating portions of an electrosurgical generator display screen with transitional graphical user interface that forms no part of the claimed design. The herein disclosed colors are only ornamenteally related to the indications and states as described above and Applicant specifically disclaims any functional relationship of the ornamental colors and/or patterns disclosed herein to the states of the generator and/or a medical procedure.
